UNITED STATES PATENT OFFICE

HARRY A. YEIDER, OF GRAND RAPIDS, MICHIGAN, ASSIGNOR TO AUTOMATIC MUSICAL INSTRUMENT COMPANY, OF GRAND RAPIDS, MICHIGAN, A CORPORATION OF DELAWARE

REPRODUCING SYSTEM

Application filed April 23, 1930. Serial No. 446,490.

My invention relates in general to a reproducing system for translating sound waves into variable electric current and transmitting the same to a remote point.

More specifically, the invention relates to an improved circuit arrangement for causing sound waves to be translated into electrical waves by means of a variable condenser of novel construction. In the embodiment of my invention illustrated in the attached drawing I have applied my invention to a phonograph reproducer or "pickup" device. In this embodiment the variable condenser of my invention is operated by the needle of the phonograph and translates the mechanical vibrations or convolutions of the record groove into corresponding electrical waves.

Among the features of my invention are the provision of an improved translating and amplifying system for reproducing sound; to provide a novel reproducing system employing a variable condenser, to provide a condenser pickup for phonographs which gives truer reproduction and greater amplification due to the design of the circuit and to the fact that the moving parts are simpler, lighter and have exceptionally free movement.

The embodiment by means of which I have chosen to illustrate my invention is shown in the accompanying sheet of drawing in which

Fig. 1 is a top view of the tone arm of a phonograph with certain parts thereof shown in section.

Fig. 2 is a view of the device of Fig. 1 taken from the bottom of Fig. 1 and also having most of its parts shown in section.

Fig. 3 is an end view taken from the right of Fig. 2 also having certain parts shown in section.

Fig. 4 is a view taken from the bottom of Fig. 3 to more clearly show the arrangement of the parts.

Fig. 5 is a circuit diagram showing the electrical connections and circuit operation of the improved translating and amplifying system.

It has become common practice since the

combination of radio receiving sets and phonographs to use the so-called magnetic pickup for translating the mechanical vibrations of the needle into electrical waves for transmission to the loud speaker. Although such devices have been fairly satisfactory I have found that the present design of a variable condenser pickup gives greater volume, truer tone, and less distortion due to the lighter moving parts.

Referring to the accompanying drawing, Figs. 1 and 2, I have shown at 1 the usual mounting for a phonograph tone arm. Connected thereto and rigid therewith is a thin metal tube 2 with its ends closed with parts 3 and 4, each of which has a rubber bushing in a socket on its inner face. The stylus bar 5 is mounted at each end in these bushings 6 and 7. The stylus holder 8 is secured to bar 5 on an angle as shown preferably by solder or a rigid joint of any type and extends down through a large opening in the lower side of tube 2 as shown. A spring and plunger needle ejector is mounted inside the stylus holder. On the opposite end of the stylus bar 5 is another hole threaded to receive a stud 9 which also projects out through a large opening in tube 2 down inside the dome mounting 1. The lower end of stud 9 is reduced to a small diameter and mounted thereon by a set screw 10 is a copper plate 11 which has an enlarged upper portion containing a hole which fits over the reduced end of stud 9, and which is adjustably held by set screw 10. Around the tube 2 and inside the dome mounting 1 is a U-shaped metallic bracket 12 inside of which is a thin metal retaining member 13, also U-shaped and fitting tightly around the tube 2. Both brackets 12 and 13 are secured together at the top and also secured to the tube 2 by soldering or other means. The bracket 13 at its lower ends has extending arms 14 and 15 which are bent outward and fit snugly around bracket 12 to hold it rigid, lugs 14 and 15 are also soldered or secured to bracket 12. Bracket 14 has an extending tip 14' which may be used as one terminal of the condenser. In one of the lower ends

of bracket 12 (Figs. 3 and 4) is an insulating bushing 16 through which extends a stud 17 which is welded to and supports a copper plate 18 adjacent the plate 11. Between the plates 11 and 18 is a dielectric of paper, mica, or other insulating material shown at 19 and the plate 18 is held clamped close to the dielectric by nuts 20 and 21 which also hold a copper terminal 22 in contact with stud 17 and therethrough to plate 18 to provide a second terminal for the condenser. In the lower end of the other arm of bracket 12 is a stud 23 threaded into a hole in the bracket and having a soft rubber bumper 24 on its inner end which may be thus pressed against plate 11 to adjust the pressure of the plate 11 on the dielectric 19. The stud 23 is locked in place by a nut 25.

Inside the tube 2 is a pliable substance which holds the stylus bar 5 and surrounds it but still permits movement thereof. The mounting of the stylus bar and the pliable material are the subject of a prior application and are shown here only as an adjunct to my present invention.

As is usual in such devices, the tone arm is mounted as indicated in Fig. 2 by a universal joint to a platform such as 26, only parts of which are shown. Thus it will be seen that when the stylus 8' is placed on a record the sidewise movement thereof when following the curves or convolutions of a groove in a record will be communicated through the stylus bar 5 to the stud 9 and thence to the copper plate 11. The corresponding sidewise vibrations of plate 11 will cause variations of the capacity of the condenser formed by plates 11 and 18 and the dielectric 19 by varying the distance between the plates.

Referring now to the circuit diagram shown in Fig. 5, I will explain the connection and function of the variable condenser shown in Figs. 1-4. At V I have shown a well known type of 3-element vacuum tube having filament, grid, and plate. The tube may be the direct or alternating current type of tube as desired and will of course have the usual connections to a battery for energizing the filament, a connection to C battery through resistance 27 for biasing the grid, and the usual B battery connections to the plate, the output to loudspeaker or the like may be taken through the primary of a transformer such as shown at 28 if desired. As any type of tube may be used, I have not shown the A, B, and C batteries but only indicated the same by letters.

Across the input of the tube I connect a source of high potential direct current of a value which may be approximately 500 volts as shown. The positive side of the direct current source is connected through resist-

ances 29 and 30 and through a series condenser 31 of fairly high capacity to the grid of tube V. The negative side of the 500 V source is connected to the midpoint of a resistance 32 bridged across the filament of the tube. A condenser 33 is bridged from the negative side of the high potential source to the midpoint between resistances 29 and 30 and these two resistances 29 and 30 and condenser 33 act as a smoother for the high potential direct current source to prevent variations or undulations in the voltage thereof from reaching the tube. At a point between the resistance 30 and condenser 31 the variable condenser 34, which comprises plates 11 and 18, has one of its plates connected and the other plate is connected to the negative side of the high potential battery.

It is well understood that variations in the impressed electromotive force on the grid of the vacuum tube cause variations in the flow of electrons between filament and plate and produce amplified changes in the current flowing in the output circuit of the tube. It will be seen, therefore, that as the needle or stylus 8' causes variations in the capacity of condenser 34 by compressing plates 11 and 18, that the said variations in capacity of condenser 34 will cause variations in the charge carried by the condenser 31 and therefore cause a correspondingly varying voltage to be set up in the grid circuit of the tube V. As long as condenser 34 is not varied the tube is inactive and the condensers 34 and 31 stand charged. The use of the high voltage and the connection of the variable condenser 34 as shown causes sharp and rapid changes in the grid potential and correspondingly strong and rapid current changes in the plate circuit resulting from changes in capacity of condenser 34.

The action of the circuit will be understood by those skilled in the art, and it will be seen that as the capacity of condenser 34 is increased by plates 11 and 18 coming close together, it will cause a lowering of the potential on grid of tube V. Also as plates 11 and 18 are drawn apart and the capacity is decreased, a current will flow through condenser 31 and in the opposite direction over and above traced circuit, to cause consequent increases of the voltage on the grid.

It will be seen, therefore, that I have provided a very efficient and simple type of pickup and that very slight movement of the plate 11 of condenser 34 produces corresponding amplified fluctuations in the plate circuit of the amplifier. As previously suggested, although the invention is illustrated as a phonograph pickup, it should be understood that the plate 11 of condenser 34 may, if desired, be vibrated directly by a diaphragm or in any other desired man-

ner to reproduce sound, and also that various changes may be made in the detailed arrangement illustrated without departing from the spirit of the invention.

- 5 Having fully described and ascertained the features and aspects of my invention, what I consider to be new and desire to have protected by Letters Patent will be pointed out in the appended claims.
- 10 What is claimed is:
1. In a device of the class described, a pickup supporting arm having a rod yieldingly supported therein, a stylus mounted on one end of said rod, a plate mounted 15 on the opposite end of said rod, another plate adjacent said first plate and a dielectric between the plates forming a condenser, the vibrations of the stylus causing corresponding vibrations of the first plate 20 through the medium of said rod and consequent variations in the capacity of the condenser.
  2. In a device of the class described, a variable condenser comprising a stationary 25 plate and a movable plate, a dielectric separating said plates, a rod supporting said movable plate on one end thereof, a stylus mounted on the opposite end of said rod and extending sidewise therefrom and ar- 30 ranged to communicate its vibrations to the condenser by rotating said rod on its own axis to vary the capacity of said condenser, means for adjusting the normal capacity of the condenser by spacing the movable plate 35 from the stationary plate, and means responsive to the variations in capacity of the condenser for producing corresponding electrical variations in a circuit.
  3. In a device of the class described, a 40 pickup supporting arm pivotally mounted at one end, the other end being rotatable about said pivoted end, a condenser mounted on the pivoted end of said arm, a stylus mounted on the movable end of said arm 45 and having means for producing variations in the capacity of said condenser, and means responsive to the capacity variations of the condenser to produce corresponding electrical variations in a circuit.
- 50 In witness whereof, I hereunto subscribe my name this 17th day of April, A. D. 1930.

HARRY A. YEIDER.
